UNITED STATES PATENT OFFICE.

JOSEPH F. SURRIDGE, OF CHICAGO, ILLINOIS.

PRESSED STEEL WHEEL AND METHOD OF PRODUCING THE SAME.

1,416,524.

Specification of Letters Patent. Patented May 16, 1922.

Application filed November 30, 1921. Serial No. 518,880.

To all whom it may concern:

Be it known that JOSEPH F. SURRIDGE, citizen of the United States of America, residing at Chicago, in the county of Cook and State 5 of Illinois, has invented new and useful Improvements in Pressed Steel Wheels and Method of Producing the Same, of which the following is a specification.

The object of the invention is to provide 10 a pressed steel wheel suitable for automobiles and similar vehicles under conditions insuring strength, efficiency and durability of the product with the minimum cost of production; and with this object in view the invention consists in a procedure of which a typical embodiment is indicated in the accompanying drawing, wherein;

Figure 1 is a side view,
Figure 2 is an edge view, and
20 Figure 3 is a sectional view taken diametrically of a wheel constructed in accordance with the improved method.

Figure 4 is a sectional view of a blank for use in forming the web and rim of the 25 proposed wheel.

Figures 5 and 6 are respectively side and sectional views of die members disposed in opposed relations preparatory to the operation of forming the hub, and showing the 30 web blank and hub billet in operative relation.

Figure 7 is a sectional view similar to Figure 6 showing the die members and plungers in the position which they assume at the 35 completion of the formation of the hub.

Figure 8 is a sectional view of die members for forming the web, arranged in spaced relation with the blank and formed hub, the product of the preceding step in the method 40 being arranged in operative relation therewith.

Figure 9 is a sectional view similar to Figure 8 with the die members in operative relation to produce the desired contour of web 45 and rim.

Whereas modification in the shape of the web and rim may be produced by the method herein contemplated, the preferred contour is shown in Figures 1 to 3 inclusive which 50 illustrate a wheel having a bowed web 10 and a rim 11 formed as a continuation or extension of the web and provided at its free edge with an outwardly directed flange 12 (the production of which, however, is optional and will depend upon the character and designed purpose of the wheel) and the

hub 13 which is molded to engage and anchor the inner edge of the web and in the finished article forms therewith an integral construction. 60

In the production of this article it is proposed to prepare a web blank 14 from a flat plate of suitable material (such as steel), with a central opening 15, the inner edge of the blank bounding said opening being 65 flanged or deflected as shown at 16, and in this connection to employ a billet 17 of suitable metal which arranged as indicated in Figures 5 and 6 in operative relation with the male and female die members 18 and 19 70 are heated to a welding temperature, the billet being disposed in the central opening of the web blank and of a volume suited to the size of the hub to be produced and which is defined by the mating cavities 20 and 21 75 in said die members. In connection with the die members there are employed the complementary cooperating plungers 22 and 23, so that when the die members are brought together as shown in Figure 7 and the plungers are moved by any suitable means to the positions indicated in said figure the metal forming the billet is forced into the form defined by the complementary rests 20 and 21 to embrace and incorporate the deflected flange portions 16 of the web blank, it being understood that said flange portions 80 are also heated to a welding temperature to combine with the material of the billet. 85

Having proceeded so far the blank with 90 the attached hub is in condition to be arranged in operative relation with the forming die shown in Figures 8 and 9 consisting of the male and female members 24 and 25 which when brought into cooperative relation by suitable hydraulic or other means produce the web and rim construction defined by the complementary faces thereof. 95

Having described the invention, what is claimed as new and useful is:— 100

1. The method of producing an integral metallic wheel hub which consists in forming a circular blank with a central opening, placing a billet of metal in the said opening, the billet and the edge of the blank surrounding the opening therein being heated to a welding temperature and then spreading and molding the billet to incorporate the edge of the blank bounding said opening. 105

2. The method of producing an integral metallic wheel hub which consists in forming a circular blank with a central opening, plac-

ing a billet of metal in the said opening, the billet and the edge of the blank surrounding the opening therein being heated to a welding temperature and then spreading and 5 molding the billet to incorporate the edge of the blank bounding said opening and finally pressing the surrounding portion of the plate to form the wheel web and rim.

3. The method of producing an integral 10 metallic wheel hub which consists in forming a circular blank with a central opening, deflecting the marginal edge of the opening from the plane of the blank, placing a billet of metal in the said opening, the billet and 15 the edge of the blank surrounding the opening therein being heated to a welding temperature and then spreading and molding the billet to incorporate the edge of the blank bounding said opening.

4. The method of producing an integral metallic wheel hub which consists in forming a circular blank with a central opening, deflecting the marginal edge of the opening from the plane of the blank, placing a billet of metal in said opening, and then finally 20 spreading the billet in the presence of a welding heat to incorporate the edge of the blank bounding said opening. 25

5. A pressed metal wheel consisting of a disk formed with a central opening having 30 the surrounding edge laterally deflected from the plane thereof, and a hub of transversely expanded material in which the said deflected edge is embedded and welded.

In testimony whereof he affixes his signature. 35

JOSEPH F. SURRIDGE.
